UNITED STATES PATENT OFFICE

160,224

ATTACHMENT FOR TELEPHONE BASES

James P. Smyth, Chicago, Ill.

Application October 22, 1949, Serial No. 5,648

Term of patent 14 years

(Cl. D26—14)

To all whom it may concern:

Be it known, that I, James P. Smyth, a citizen of the United States, residing at Chicago, in the county of Cook and State of Illinois, have invented a new, original, and ornamental Design for an Attachment for Telephone Bases, of which the following is a specification, reference being had to the accompanying drawings forming a part thereof.

Fig. 1 is a perspective view of an attachment for telephone bases showing my new design; and

Fig. 2 is a perspective view of the underside of the same.

The dotted lines shown in Fig. 1 are for illustrative purposes only.

I claim:

The ornamental design for an attachment for telephone bases, substantially as shown and described.

JAMES P. SMYTH.
